UNITED STATES PATENT OFFICE.

CHARLES W. McMASTERS, OF ELWOOD, INDIANA.

GATE-OPERATING DEVICE.

No. 802,307.

Specification of Letters Patent.

Patented Oct. 17, 1905.

Application filed November 5, 1904. Serial No. 231,548.

To all whom it may concern:

Be it known that I, CHARLES W. McMASTERS, a citizen of the United States, residing at Elwood, in the county of Madison and State 5 of Indiana, have invented a new and useful Improvement in Gate-Operating Devices, of which the following is a specification.

This invention is an improved construction of gate-operating device, the object being to 10 provide an exceedingly cheap and simple device which can be easily operated by the approach of a vehicle in either direction.

Another object of the invention is to so construct the operating rods and levers that 15 all of the parts will be held in a locked position when not in operation.

With these various objects in view the invention consists in the novel features of construction and combination of parts hereinafter 20 fully described, and pointed out in the claims.

In the drawings forming a part of this specification, Figure 1 is a perspective view showing the practical application of my invention. Fig. 2 is a sectional elevation. Fig. 25 3 is a detail section on the line 3 3 of Fig. 2. Fig. 4 is a perspective view showing the upper portion of the hinge. Fig. 5 is a perspective view showing the lower portion thereof. Fig. 6 is an enlarged plan view of 30 the joint between the operating-rods. Fig. 7 is a detail sectional view on the line 7 7 of Fig. 6.

Referring to the drawings, A indicates the post to which the hinges are connected, and 35 B the batten of the gate, to which the hinges are also connected.

C C indicate the collars rigidly fastened to the post A, each collar having an outwardly-projecting flange C', the upper face of which 40 is grooved, as shown at C'', and adapted to receive the antifriction-balls D.

Collars E E are fitted loosely upon the post A, each collar being provided with a flange E', grooved as shown at E'', said collars E being arranged above the collar C, so that the 45 balls D will be held between the grooved flanges of the two collars. The collars E are connected to the gate by means of arms F, provided with parallel ears or plates G, which 50 are bolted to the end batten of the gate, as most clearly shown. Pull-rods H are pivotally connected to the lower collar E at diametrically opposite points, each point of attachment being ninety degrees from the arm 55 F. The opposite end of each pull-rod is connected to a cranked tripping-lever I, the end

of the rod being formed with a transverse sleeve H', in which the end of the tripping-lever works, said lever being provided with a lug I', which works in a cam-groove H'', produced in the sleeve H', and by means of which the rod H is shifted laterally as the lever I is tripped when a wheel strikes the same when approaching the gate, the purpose of the said lateral shift of the end of the thrust-rod H being to throw the line of thrust obliquely instead of in a straight line with the center of the post, thereby causing the lower collar to be turned, and consequently the gate. 60 A rod K has a bifurcated end K', which fits upon the end of the crank tripping-lever and embraces the sleeve H' at the end of the rod H, as most clearly shown in Fig. 6. The opposite end of each rod K is connected to a cranked tripping-lever L, which normally 70 rests in a position at right angles to the position of the adjacent cranked lever I. It will thus be seen by reference to Fig. 1 that both levers L are down and both levers I are up, and a vehicle in approaching the gate from 75 either direction will strike the lever I and operate the rod H and open the gate, the lever I being depressed during the said operation and the lever L moved to an upright position. As the vehicle passes through the gate it first 80 passes over the other lever I, which is in a lowered position, and then contacts with the other lever L, which is in a raised position, and forcing said lever down serves to raise the other lever I, and consequently close the gate. The 85 sleeve H' is also provided with shoulders H''' to limit the up-and-down movement of the said sleeve with reference to the bifurcated end of the rod K, said shoulders contacting with said end and acting as stops and holding the rods 90 practically locked in their raised and lowered positions.

It will thus be seen that I provide an exceedingly simple construction of gate-operating means which will efficiently carry out all of 95 the objects hereinbefore mentioned.

Having thus fully described my invention, what I claim as new, and desire to secure by Letters Patent, is—

1. The combination with the post and gate, 105 of the fixed collars arranged upon the post, the movable collars connected to the gate and movable upon the fixed collars, rods connected to the lower movable collar at diametrically opposite points and provided with sleeves at 110 their outer ends, said sleeves having internal cam-grooves, the cranked tripping-levers,

each provided with a lug engaging the cam-groove in the sleeve, the pull-rods having a bifurcated end through which the end of the crank tripping-lever passes and a second set 5 of cranked tripping-levers connected to the outer ends of the pull-rods as set forth.

2. The combination with the gate and post, of the fixed grooved collars, the movable grooved collars attached to the gate, the anti-friction-balls arranged between the grooved faces of the collars, the rods pivotally connected to the lower movable collar at diamet-

rically opposite points, the opposite ends of said rods being provided with grooved sleeves, the cranked tripping-levers provided with 15 lugs engaging the grooves in said sleeve, the pull-rods connected to the said tripping-levers and first-mentioned rods, and a second set of cranked tripping-levers all arranged and adapted to operate substantially as described. 20

CHARLES W. McMASTERS.
